[57] CLAIM

The ornamental design for a display cabinet, as shown
and described.

DESCRIPTION

FIG. 1 is a front perspective view of a display cabinet
showing my new design;

FIG. 2 is a front elevational view thereof;

FIG. 3 is a left side elevational view as seen when in use,
the right side being a mirror image thereof; and

FIG. 4 is a top plan view thereof.

FIG. 1

FIG. 2

FIG. 3

FIG. 4
